United States Patent Office

Des. 233,255
Patented Oct. 15, 1974

233,255

MICROFICHE VIEWER

Peter Joseph Hall, Willowdale, Ontario, Canada, assignor
to Microfilm Recording Co. Ltd., Weston, Ontario,
Canada

Filed Jan. 29, 1973, Ser. No. 327,478

Term of patent 14 years

Int. Cl. D16—02

U.S. Cl. D61—1 N

FIG. 1

FIG. 2

FIG. 3

FIG. 1 is a right front perspective view of a microfiche viewer showing my new design;

FIG. 2 is a front elevational view thereof;

FIG. 3 is a rear elevational view thereof;

FIG. 4 is bottom plan view thereof;

FIG. 5 is a left side elevational view thereof; and

FIG. 6 is a top plan view thereof.

I claim:

The ornamental design for a microfiche viewer, substantially as shown.
